Primary Examiner — Austin Murphy

(74) *Attorney, Agent, or Firm* — Duane Morris LLP

(57) **CLAIM**

The ornamental design for a drying rack, as shown and described in the Figures.

DESCRIPTION

FIG. 1 is an isometric view of the drying rack in an extended position;

FIG. 2 is a front elevation view of the drying rack in the extended position;

FIG. 3 is a rear side view of the drying rack in the extended position;

FIG. 4 is a side view of the drying rack in the extended position;

FIG. 5 is a side view of the drying rack from the opposite side illustrated in FIG. 3 in the extended position;

FIG. 6 is a top side view of the drying rack in the extended position;

FIG. 7 is a bottom side view of the drying rack;

FIG. 8 is an isometric view of the drying rack in a collapsed position;

FIG. 9 is a front elevation view of the drying rack in the collapsed position;

FIG. 10 is a rear side view of the drying rack in the collapsed position;

FIG. 11 is a side view of the drying rack in the collapsed position;

FIG. 12 is a side view of the drying rack from the opposite side illustrated in FIG. 11 rack in the collapsed position;

FIG. 13 is a top side view of the drying rack in the collapsed position;

FIG. 14 is a bottom side view of the drying rack in the collapsed position; and,

FIG. 15 is an isometric view of the drying rack in a further expanded position.

1 Claim, 13 Drawing Sheets
